Attorney

UNITED STATES PATENT OFFICE.

JOHN G. ARMKNECHT, OF DETROIT, MICHIGAN.

FUEL-RESERVE TANK.

Original application filed January 30, 1922, Serial No. 532,613. Divided and this application filed July 19, 1923. Serial No. 652,555.

To all whom it may concern:

Be it known that I, JOHN G. ARMKNECHT, a citizen of the United States of America, residing at Detroit, in the county of Wayne and State of Michigan, have invented certain new and useful Improvements in Fuel-Reserve Tanks, of which the following is a specification, reference being had therein to the accompanying drawings.

10 This invention relates to improvements in fuel reserve tanks, pertaining more particularly to structures adapted to contain a supply of fuel normally segregated from the normal supply for the explosive engine, and capable of being used as a supply at the will of the operator. The present application is a division of that filed by me January 30, 1922, Serial No. 532,613.

20 The invention pertains to that general type which is designed to meet emergency conditions in the operation of motor vehicles, viz: conditions where the supply of fuel becomes exhausted and it becomes necessary to replenish the supply; this condition generally arises at points removed from a service station, the result being that it is necessary to travel to the station in order to obtain a supply and then return to the "dead" motor vehicle in order that the supply may be replenished. To meet this condition it has become the practice to carry a relatively small quantity of fuel normally inaccessible for use as the usual source of supply.

30 A number of ways of meeting this condition have been employed, some of which involve the use of special structures within the supply tank with the openings at different levels, the usual supply being made accessible through the opening of higher level, the fuel remaining between this level and a lower level constituting a reserve; in such structures it becomes necessary not only to employ a special formation within the tank 40 or an auxiliary to the tank, but also to manipulate valve structures as well as to require the attention of the operator to see that the valve maintains the reserve free from loss, as by accidental opening of the valve through use of the vehicle. Another way of meeting the condition is to employ an auxiliary tank, which may or may not be located within the main tank, this auxiliary tank, when located within the main supply tank being generally located in a posi-

tion relative to the filling opening of the main supply tank and forming the channel through which the fuel reaches the main tank.

The present invention is of that type 60 which employs the auxiliary tank and has for its object the provision of a receptacle which, while extending into the supply tank when in position, is removable from the tank or shiftable relative to the filling opening during the time the tank is being filled, thus permitting the filling operation to place the fuel directly within the main supply tank. This result may be obtained in various ways, but is preferably obtained by 65 mounting the receptacle on the filling cap, so that the latter may be readily moved into and out of its closure position while maintaining the integrity of the reserve, the auxiliary or reserve tank moving with the 70 cap and being capable of removal from the tank bodily with the cap or shiftable with the cap relative to the filling opening in such manner that the supply tank can be readily filled.

75 Another object is to provide for automatic filling of the reserve tank when in position, if such filling is required, the arrangement being such as to permit of ready controllable discharge of the fuel from the reserve tank into the supply tank by removal of the reserve tank from the supply tank.

80 Further objects are to provide a construction which is simple and efficient in operation, durable in construction, readily installed without change in the usual tank structures and which can be manufactured at a relatively low cost.

To these and other ends, therefore, the 85 nature of which will be readily understood as the invention is hereinafter disclosed, said invention consists in the improved construction and combination of parts hereinafter more fully described, illustrated in the accompanying drawings, and more particularly pointed out in the appended claims.

90 In the accompanying drawings, in which similar reference characters indicate similar parts in the several views,

Figure 1 is a perspective view showing 105 one embodiment of the present invention.

Fig. 2 is a longitudinal sectional view of the structure of Fig. 1 with the reserve tank shown in its normal or carrying position within the supply tank.

22
 Fig. 3 is a detail sectional view of the upper portion of the reserve tank, the section being taken at right angles to that of Fig. 2.

5 For the purpose of illustrating the invention I have shown it as applied to a tank 10 having a screw-threaded filling opening 11, this form of tank being simply illustrative of any one of a large number of tanks in 10 commercial use, the filling opening being usually closed by a filler cap having threads adapted to co-operate with the threaded filling opening.

In the present invention the usual filler 15 cap is substituted by a cap 12 having the external threaded zone to permit of engagement with the threads of the filling opening, and a reserve tank 13 secured to the cap so as to depend from the cap within tank 10 20 in alignment with the filling opening so that, when the cap is bodily removed, the reserve tank will be removed with it. In the application of which the present is a division, I have shown several ways in which the invention 25 may be carried into effect; in each, however, the tank 13 is provided with a permanently closed bottom 13^a as well as a top 13^b that is permanently fixed to the tank or container longitudinal walls, and which 30 is of a generally closed characteristic, the top 13^b, however, in the present embodiment of the invention carrying openings 13^c, one or more of which may be filling openings, each of the openings, of course, being serviceable as vent openings. In addition, the underside of the top 13^b may carry a baffle 35 18 underlying openings 13^c and serving to tend to break down any tendency to throw out fuel from the reserve tank under splashing conditions, and at the same time permit of ready drain of fuel content that may be 40 on the upper face of the top and ready removal of the fuel content from the interior of tank 13 when the reserve supply of fuel 45 is to be put into service.

The reserve tank may be filled direct, but is designed more particularly to be filled by the splashing activity within the main tank. As will be seen the top 13^b is depressed with 50 respect to the upper ends of the longitudinal wall of the tank, thus forming a shallow portion within which the splashing content may pass and be collected, such content passing into the interior of tank 13. Splashing within the main tank is inevitable and when the tank is in its approximately filled condition the splashing will take place in the immediate vicinity of this shallow top so that considerable quantity of the fuel 55 content will rapidly pass into tank 13 by draining. As the level in the main tank lowers, the splashing condition remains but there is less likelihood of the supply for tank 60 13 continuing at the higher rate; but it will 65 be understood that any content that may be

splashed on to the top 13^b will find its way into the interior of tank 13, at least until the latter is practically filled.

As will be understood, the use of the splashing activity as the source of supply 70 for tank 13 requires that the shallow top be sufficiently spaced from the top of container 10 as to permit the content to freely pass into position where it reaches the shallow top, and hence it is essential that the top of 75 tank 13 be spaced from the cap 12, although secured to it. Any suitable form of connection between the cap and tank may be employed, but I prefer to employ a connection 80 having the general characteristics of the U-shaped member 15, the two legs 15^a of the member being secured respectively to the under face of the cap and the upper face of top 13^b the position of the member being 85 such that the bridge or connecting portion is considerably "off-center." Since the legs are spaced apart a distance greater than the length of the filling opening 11, it will be understood that the open space between the legs may receive the wall of the filling opening, as shown in dotted lines in Fig. 2, an arrangement which permits the filling of the main tank without removing the reserve tank, the cap being unscrewed—member 15 90 permitting this action without any difficulty—and when free from the filling opening, the cap is pushed to one side to overhang the wall of the filling opening and provide a support for the reserve tank leaving the filling opening sufficiently unobstructed to permit ready filling of the main tank. When the later has been filled, the cap is shifted into threading position and when it is threaded to its seat suspends the 95 tank 13 within its proper position.

100 The cap 12 may be of any preferred formation, although I prefer to employ that shown in the parent application, in which it is shown as having a depressed portion 12^a within which are located wings 12^b 105 which permit ready removal of the cap by the use of the fingers of the hand; and I prefer to provide the cap with a venting opening as in cap structures generally.

110 As will be understood the reserve tank may be automatically filled by the splashing of the content of the main tank. Initially, it may be desirable to provide a quantity 115 within the reserve tank to meet the possibility of use should exhaustion of the first filling of the main tank require the use of the reserve; however, this is not necessary where the operator of the car replenishes the main supply before exhaustion, succeeding fillings of the main tank producing conditions under which the reserve tank will 120 become filled and maintained in such condition. When required for use the reserve tank is withdrawn and its content permitted 125 to flow out through openings 13^c into the 130

main supply tank, thus placing into use a reserve supply that will carry the automobile a considerable distance and enable a fuel station to be reached.

5 Claims to the broad combination that includes member 15 are not presented herein since these are presented in the parent application.

As will be understood, I have provided 10 a construction which is capable of use with practically all the commercial forms of supply tanks, a construction which is simple and efficient in operation, durable in construction, and which can be manufactured 15 at a comparatively low cost.

While I have herein shown one way in which the invention may be carried into effect, it will be readily understood that changes and modifications therein may be 20 found desirable or essential in meeting the exigencies of use, and I desire to be understood as reserving the right to make any and all such changes or modifications as may be found desirable or necessary in so far as the 25 same may fall within the spirit and scope of the invention as expressed in the accompanying claims when broadly construed.

Having thus described my invention, what I claim as new is:—

30 1. A fuel reserve formation for motor vehicle service and comprising a closure member for the filling opening of the

fuel supply tank, and a fuel container secured to and depending from and movable with the closure, said container 35 having dimensions and a configuration to permit free passage through the filling opening, said container having a permanently-closed bottom and a permanent top, said top carrying filling and venting openings and 40 with a baffle formation underlying such openings.

2. A fuel reserve formation for motor vehicle service and comprising a closure member for the filling opening of the fuel 45 supply tank, and a fuel container secured to and depending from and movable with the closure, said container having dimensions and a configuration to permit free passage through the filling opening, said container 50 having a permanently closed bottom and having a top independent of said closure member but connected thereto and spaced therefrom providing a substantial passage-way between the supply tank to the top of 55 the container, said top having a filling port accessible to the fuel content of the main tank during periods of splashing activity.

In testimony whereof I affix my signature in presence of two witnesses.

JOHN G. ARMKNECHT.
